UNITED STATES PATENT OFFICE.

ARNOLD STERN, OF NEW YORK, N. Y., ASSIGNOR, BY DIRECT AND MESNE ASSIGNMENTS, TO THE ANNULO STOPPER COMPANY, OF NEW JERSEY.

BOTTLE-STOPPER.

SPECIFICATION forming part of Letters Patent No. 677,900, dated July 9, 1901.

Application filed December 15, 1900. Serial No. 40,030. (No model.)

To all whom it may concern:

Be it known that I, ARNOLD STERN, a citizen of the United States, residing in the borough of Manhattan, in the city of New York, county 5 and State of New York, have invented certain new and useful Improvements in Bottle-Stoppers, of which the following is a specification.

My invention relates to bottle-stoppers, and 10 its novelty consists in the construction and adaptation of the parts.

It has long been desirable to produce a non-corrosive bottle-stopper which would be as cheap as or cheaper than cork and one which 15 would at the same time be elastic and impervious to liquids. In my invention I believe that I have produced a stopper which has all of the advantages and none of the disadvantages of cork and which at the same time is 20 cheaper and can readily be introduced into and removed from the bottle.

It consists, in brief, of a flat disk designed to be placed in the bottle at right angles to its longitudinal axis, so as to close the mouth 25 of the bottle, and provided with a continuous external annular flange made by bending downward and outward, then upward and inward, a portion of the material of the disk to form an annulus in whole or in part, the 30 whole being made of a diameter slightly larger than that of the aperture to be closed thereby. The stopper so formed is thus provided with a continuous cushioned edge; which permits of its being forced into the neck of 35 the bottle, when the elasticity of the material of which it is composed, preferably of metal, causes it to be retained in place precisely like a cork, as similarly it conforms somewhat to the shape of the internal surface of 40 the bottle.

In the drawings, Figure 1 is a top plan view, and Fig. 2 a side view, of my improved bottle-stopper. Fig. 3 is a central longitudinal section of the neck of a bottle, showing the bottle- 45 stopper in section as it is made to approach the mouth of the bottle. Fig. 4 is a similar view showing its position after it has been

further forced into the mouth of the bottle with an inclined neck, and Fig. 5 shows its position in a bottle having a straight neck. 50

In the drawings, *a* is the disk of my improved stopper, made of flexible metal or other suitable material. At its outer circumference the material is curved downward, outward, upward, and inward to form a continuous external annular flange *b*. I prefer that the annulus should not be completely closed, on account of the tendency to buckle which results from that form of construction. 55

When it is designed to close a bottle with my improved stopper, it is first placed upon the rim of the mouth, as shown in Fig. 3, and a suitable plunger, provided with an under surface conforming to the upper surface of the stopper, is brought to bear upon it toward the interior of the bottle. If now the downward action of the plunger is continued, the stopper is squeezed or forced into the mouth of the bottle precisely like a cork, its lateral external surface being made to conform to the internal surface of the bottle if the latter is slightly irregular. The annulus is elastic and at the same time it may be squeezed so as to form a tight joint with the interior surface of the neck of the bottle. The overhanging inwardly-projecting edge of the flange affords resistance to the pressure created between the stopper and the neck of the bottle and affords a means for readily removing the stopper from the bottle, as a tool may be inserted under this overhanging edge to force the stopper upward and out of the bottle. 75 80

The stopper may be made of any suitable material, although I prefer some moderately light flexible metal like aluminium or an alloy of aluminium and tin. I may also coat the inner surface of the stopper with waxed paper or the like; but such refinement is not really necessary. 85

The simplicity of my device is its great advantage. It requires no gaskets to be used with it and does not require a bottle to be made to conform to its shape or the manner of placing it in position. Any bottle having 90

an approximately circular form in cross-section may be closed with my stopper.

What I claim as new is—

5 A bottle-stopper consisting of a disk bent downwardly and outwardly, upwardly and inwardly, to form a continuous surrounding annular elastic flange, the edge of which is extended inward over, or toward the center of, the disk, the whole being made slightly

larger in diameter than the aperture designed to be closed thereby.

Witness my hand this 12th day of December, 1900, in the presence of two subscribing witnesses.

ARNOLD STERN.
